MEANS FOR COMMUNICATING TRANSFER MEDIUM

Samuel A. Neidich, Burlington, N. J., assignor, by
mesne assignments, to Underwood Elliott Fisher
er Company, New York, N. Y., a corporation of
Delaware

Application January 2, 1936, Serial No. 57,165

1 Claim. (Cl. 91—54)

This invention relates to means for communicating transfer mediums, according to a novel principle, one of its applications being to ink or re-ink the ribbons of writing, duplicating, and stencilling machines, or the like, though the use of the invention is not restricted to the particular field mentioned.

Broadly, one object of the present invention is to effect the communication of ink or other transfer medium, either wet or dry, from a suitable flexible carrier charged with such medium to a second flexible carrier, which may be totally or partially deficient in such medium, such communication being effected by intervolving or intercoiling the charged and deficient carriers, drawn from independent sources, so that the fakes or courses of the charged and deficient carriers lie in intimate contact wherein they remain for an appreciable length of time, after which, the carriers are unwound or uncoiled from the single reel on which they were intercoiled, and onto their individual reels for packaging or other purpose.

Another object is to effect the intercoiling or interwinding of the charged and deficient flexible carriers under tension, whereby to facilitate the exchange of the transfer medium from the charged carrier to the deficient carrier by opening the pores or interstices of the deficient carrier to render it more absorbent, as well as rendering it more adherescent, and by slightly extending the charged carrier in the direction of its length, to so alter the shapes of the pores or interstices thereof as to effect an expression or extrusion of the medium with which it is charged, coated or impregnated, onto the closely pressed abutting surface of the deficient carrier, the pores of which have been similarly opened to receive such material.

The invention finds a large field of usefulness, not only in the application of a transfer medium from a carrier charged, coated or impregnated therewith, to a carrier wholly or completely deficient in such medium, but also in the discharge of a transfer medium from a supercharged carrier to condition such carrier for practical use.

Still another object is to provide for the re-inking of flexible carriers, as ribbons exhausted of ink, in a neat and cleanly manner, without soiling the person or garments of the operator, the amount of handling necessary to apply and remove the ribbons being reduced to a minimum, the parts being most accessible, occupying but little space, and of simple construction to avoid

liability of getting out of order, and to facilitate operation of the device.

To these and other ends, the invention includes certain novel features, and combinations of parts, which will be more fully disclosed hereinafter and particularly set forth in the claim.

In the accompanying drawings:

Figure 1 is a top plan view of a simple form of mechanism, illustrating one embodiment of the invention;

Figure 2 is a vertical sectional view, taken on line 2—2 of Fig. 1;

Figure 3 is a diagrammatic view, illustrating the unwinding of the intercoiled ribbons from the multiple ribbon holder to the individual ribbon holders;

Figure 4 is a detail perspective view of one form of a ribbon support;

Figure 5 is a diagrammatic view, illustrating a slightly different arrangement of ribbon supports, showing the two independent sources of ribbon supply located to one side of the intercoiling support;

Figure 6 is a diagrammatic view, showing the use of two sets of flexible carriers with a single intercoiling support;

Figure 7 is a top plan view of a modification of the disclosure in Fig. 2, showing the use of several carriers on the same supports.

The desirability of re-inking ribbons exhausted of ink by use in writing machines, as typewriting, adding and calculating machines, and in multigraphing, stencilling and printing machines, has resulted in the production of a large number of devices to effect this object, most of which have proven impractical because the transfer medium, as ink, was not applied evenly to the entire surface, or was applied in insufficient quantity, or because the means for re-inking was too cumbersome and clumsy to use, as well as soiling the hands and garments of the operator, and hence, was distasteful.

The present invention departs materially from the prior art, it having developed along a substantially novel path, the nearest approach to which, so far as I am aware, being the disclosure in the U. S. Patent to Felton, No. 1,826,568, issued October 6th, 1931, wherein a pair of ribbons are wound on the ordinary ribbon spools of a typewriter, the reach of one of the ribbons between the spools, termed the writing ribbon, being led through the usual ribbon vibrator, and the reach of the remaining or ink supply ribbon, between the spools, being led from one spool to the other around an arcuate guide plate, whereby the

reaches of the two ribbons are separated, the inventive idea being to maintain the supply of ink substantially constant in the writing ribbon.

It is also an old and well-known expedient in duplicating typewriting to wind a plurality of ribbons on the spools of a writing machine and lead the group of ribbons past the printing point to enable a plurality of work sheets to be interleaved with the reaches of ribbons between the spools, which serve the purpose of carbon sheets in this instance.

The principle of my invention may be embodied in a large number of mechanical forms materially differing in structure, the accompanying drawings representing a single example of many such structures, and being more or less diagrammatic or simple in its nature, to afford a clear understanding of the invention.

A suitable base 1 supports a plurality of vertical standards 2. There are shown three such standards arranged in alinement across the base, but it will be understood that a larger or smaller number of standards arranged in other relations may be employed, a few of such variations being illustrated in Figs. 5 to 7, both inclusive.

A supply spindle 3 is journaled in any convenient manner in each of the two lateral standards, a similar spindle 4 being journaled in the center standard. As shown, the spindles are each journaled at one end in their respective standards, the bearings for the spindles extending through the standards, to expose and render accessible the ends of the spindles 3, 4, adjacent the bearings, which ends may be reduced in size and formed, as by flattening or otherwise, into tenons 5 for the reception of the socket of a suitable key or crank 6 which fits over the tenons, to enable the operator to rotate the spindles.

The opposite free ends of the spindles 3, 4 overhang the base, the spindles extending in parallelism and conveniently, but not necessarily, being arranged in the same horizontal plane.

The free end of each spindle may be reduced in diameter, as shown, for a suitable distance to form a pilot on which a reel or ribbon spool 7 or 8 may be removably slid, until it abuts a shoulder 9 (Fig. 4) formed at the juncture of the reduced free end of the spindle and its body portion.

As one convenient means to readily connect the spools 7, 8, and the spindles 3, 4, against independent rotation, I may utilize the well-known stud and recess interlock common in the typewriting machine art, for instance, wherein the hubs of the reels or ribbon spools 7, 8 are recessed, as at 10 (Fig. 4) to accommodate studs 11 projecting from the shoulders 9 parallel with the spindles.

To fully utilize the principle involved in my invention, I provide each spindle with individually adjustable means to restrain the free rotation of the respective spindles, which means may conveniently take the form of a resilient friction brake strap 12 of substantially U-shaped form, adapted to embrace its spindle. One arm of each brake strap 12 is secured to its adjacent standard, as by a stud 13 (Fig. 2), and a headed bolt 14 passes through and connects both arms of the brake strap 12, the threaded outer end of the bolt carrying a wing-nut 15, for instance, to enable the friction to be regulated or entirely relieved, depending upon the progress of the re-inking operation, and the degree of ink or other medium to be transferred.

The method or process of carrying out this

invention is as follows: The spool 7 on which is wound the ribbon or flexible carrier 19 which is deficient in transfer medium, is slipped over the free end of one of the spindles 3, and adjusted along the reduced length of spindle until one side face or flange of the spool abuts the shoulder 9 of the spindle, with the stud 11 entered in the recess 10 in the hub of the spool.

The spool 7 on which is wound the ribbon or flexible carrier 20, saturated, impregnated, coated or otherwise charged with a supply of a suitable transfer medium, is similarly applied to the remaining spindle 3.

The free ends of the ribbons or flexible carriers 19 and 20 are then led to an empty ribbon spool or reel 8 similarly mounted on the central rotatable spindle 4, the ends of the ribbons being secured to the empty spool in any convenient manner.

As illustrated in Fig. 3, the free ends of the respective flexible carriers may be secured by clips or buckles 21 of any usual form, common in the art, to the hub of the central spool 8 at diametrically opposite points thereon. Obviously, if additional deficient and charged carriers are used, the free ends of such carriers might be secured either to the same or other peripheral points on the central spool, (see Fig. 6) or the free ends of the charged and deficient carriers might be fastened to the hub of the central spool at a common point thereon, as in Fig. 5.

If desired, any suitable means may be adopted to retain the spools 7 and 8 in place on their spindles, as the removable spring-retainers 22, or the spindles may be tapered, so that the spools will fit tightly thereon.

The brakes or rotation-restraining elements 12 are then adjusted to set up a sufficient resistance to the rotation of the spindles 3, and a lesser degree of resistance to the rotation of the spindle 4, sufficient only to prevent rotation of the central spindle in unwinding direction under the influence of the tension developed in the flexible carriers 19 and 20. The operator now rotates the central spindle 4, as by the crank 6, to simultaneously unwind the respective deficient and charged flexible carriers from the spools 7 and coincidentally wind them in intercoiled relation on the central spool 4.

By reason of the tension set up in the reaches of the respective flexible carriers by the yielding rotation-restraining elements 12, the fakes or courses of the intercoiled flexible carriers are snugly laid around the hub of the central spool 22, the tension developed by the pull exerted through the crank, on the deficient carrier, operating to open and elongate the pores of the material of which the carrier is formed for the ready reception of the transfer medium communicated thereto by the closely pressed interwoven coils of the charged carrier, the similarly applied tension on which serves to extrude or express the transfer medium therefrom by deforming or stretching the charged carrier, the transfer medium being absorbed by and adhering to the deficient carrier.

Aided by the pressure or squeezing action set up in the intercoiled carriers as the winding of the separate carriers onto the central spool proceeds, the transfer medium released by the charged carrier, is forced into the deficient carrier, in addition to being absorbed thereby through capillary action of the bibulous fibres of the deficient carrier.

The time required for communicating the trans-

fer medium from the charged carrier to the deficient carrier is materially varied by varying the degree of tension under which the carriers are interwound.

5 Preferably, after the individual carriers 19 and 20 are drawn off their individual spools 7 and interwound onto the central spool 4, the process of charging or recharging the deficient flexible carrier is allowed to continue in situ, the flexible carriers being left in their intercoiled relation for a sufficient period determined by the amount of transfer medium to be communicated to the deficient carrier, or by the amount of transfer medium to remain in the charged carrier. I have 10 found that leaving a super-charged carrier in tightly intercoiled relation with an exhausted carrier, say, over night, is sufficient to recharge the exhausted carrier to a material degree, and to reduce the super-charged carrier to a medium- 15 charged condition, so that both carriers are fit for practical use.

After the carriers 19 and 20 have remained in close contact a sufficient length of time to communicate the transfer medium to the deficient 20 carrier, the intercoiled carriers may be unwound from the central spindle 4 and rewound on their original spools 1, as by applying cranks 6 to the respective spindles 3 and operating them together.

Preferably, however, the supply spindles 3, 30 which, in Figs. 1 to 3, are shown to right and left of the central spindle 4, may be equipped with sprockets 16 connected by a sprocket chain 17 to facilitate the unwinding operation, it being necessary only to apply the single crank 6 to the tenon 5 of either spindle 1, to impart rotation simultaneously to both spindles.

An important feature of the invention resides in the provision of separate sources from which the charged and deficient carriers are drawn to the common interwinding means, and the withdrawal of such carriers to separate holders or supports which may be the same from which they were originally unwound, or others, whichever is most convenient.

45 It is well known that operating difficulties are encountered when an attempt is made to wind an interwound set of flexible carriers, as ribbons, from one support onto another, due to the fact that the innermost ribbons "fan out". This is caused by the fact that the inner ribbon is coiled around a circumference which, though constantly becoming greater as the winding proceeds, is less than the circumference about which the outer ribbon is wound, so that the outer end of the 50

inner ribbon extends past the outer end of the outer ribbon.

Obviously, additional spindles may be provided for use with the single re-inking spindle 4, as shown in Fig. 6, it being possible to feed two 5 or more sets of used and charged ribbons to a single re-inking ribbon holder for simultaneous intercoiling thereon, or the spindles might pass entirely through and extend on opposite sides of their standards, as shown in Fig. 7, for the 10 reception of ribbon reels or spools on the opposite ends of each spindle, additional spools and carriers being shown in dotted lines, the outermost spools being interlocked with the inner spools by the same stud and recess means, as 15 heretofore described.

The provision of separately adjustable braking, or rotation-restraining devices on the respective spindles enables the application of uniform tensions in the unwinding of the respective 20 charged and deficient carriers, or the degree of tension under which one of the carriers is unwound from its support may be varied at will from that under which the other carrier is drawn from its support. Likewise, the tension applied 25 to the interwinding spindle may be adjusted to obtain the best results under varying conditions.

Other changes might be made in the form and arrangement of the several parts described, without departing from the spirit and scope of the 30 invention, the essence of which resides in the provision of separate or individual sources of supply for the deficient and the charged flexible carriers, respectively, and a means to which the charged and deficient flexible carriers feed, adapted 35 to intercoil the carriers under tension, and from which the carriers are unwound or paid out when the deposit or communication of the transfer medium from the charged carrier to the deficient carrier has taken place.

40 What I claim as new, is:—

In a ribbon-inking mechanism, the combination of a plurality of rotatable ribbon holders; a single rotatable ribbon holder; means to rotate the single ribbon holder to withdraw a plurality 45 of ribbons from the first-mentioned plurality of holders, and wind them on the single ribbon holder in intercoiled relation; and driving means to connect the first-named plurality of ribbon holders for simultaneous rotation, to enable rotation 50 of one of the first-named ribbon holders to turn all of such holders to unwind the intercoiled ribbons from the single holder, and to rewind the ribbons on their respective individual holders.

SAMUEL A. NEIDICH. 55
